UNITED STATES PATENT OFFICE.

OSCAR A. JOHNSON, OF WORCESTER, MASSACHUSETTS, ASSIGNOR TO RILEY STOKER CORPORATION, OF WORCESTER, MASSACHUSETTS, A CORPORATION OF MASSACHUSETTS.

TUYÈRE BLOCK.

Application filed June 22, 1925. Serial No. 38,707.

My invention relates to underfeed stokers and more particularly to a tuyère block structure adapted to serve as a grate block to support the fuel bed and to admit air thereto.

5 An underfeed stoker comprises a deep retort located between side walls surmounted by tuyère blocks which are arranged to transmit air from a passage beneath the retort to the fuel bed. One form of tuyère structure consists of narrow blocks mounted side by side in such a manner that they can be easily replaced. Since these blocks are exposed to the intense heat of the burning fuel, they are ordinarily made of a vertical web 10 portion having an outer flange supporting the fuel and ribs on the side of the web so arranged as to provide grooves therebetween which form tuyère openings between adjacent blocks.

20 The tuyère blocks as previously constructed have been so made that when the outer flange has been burned through, a hole is thus formed which communicates with the air passage beneath and lets a large volume of air escape into the fuel bed and thus detracts from the efficiency of operation of the furnace. Also this hole permits the fuel to fall into the air passage.

It is accordingly the main object of my 30 invention to overcome this difficulty and to provide a tuyère block which is so constructed and arranged that it will have a long and efficient life and provide a substantially uniform tuyère opening for the passage of air even after the block has been burned away to a considerable extent.

With this and other objects in view as will be apparent to one skilled in the art, my invention resides in the combination of parts 40 set forth in the specification and covered by the claims appended hereto.

Referring to the drawings which illustrate one embodiment of my invention:—

Fig. 1 shows somewhat diagrammatically and partly broken away a single retort stoker having side dumping plates and tuyère blocks embodying my invention; and

Fig. 2 shows in perspective view a group of tuyère blocks assembled in proper relation to each other.

In accordance with my invention, I so form the tuyère block as to provide, in addition to the usual fuel supporting flange, a

secondary flanged or ribbed structure which will serve as a fuel support when the upper 55 flange has been burned away, and which will maintain substantially the same area of air openings to the fuel as existed originally, thereby prolonging the useful life of the block.

One type of underfeed retort stoker to which this invention may be applied comprises, as shown in Fig. 1, walls 10 which form a substantially U-shaped retort within which fuel may be suitably fed from 60 outside the furnace. The retort walls are mounted on a suitable foundation 11 and spaced from the furnace walls 12 on both sides to provide room for the grate structure and dumping plates. A partition wall 13 65 is provided on each side of the retort, but one of which is shown, and the dumping plate 14 is pivotally mounted thereon by means of a suitably arranged hinge structure 15. In the construction illustrated, the retort walls 10 are turned over at their tops 70 to form substantially horizontal plate portions 16. Removable dead plates 17 are supported on the outer ends of these plates 16 and the tops of the walls 13.

In order to admit air to the fuel and to support the fuel bed at the sides of the retort adjacent the hot zone of the fire, the tuyère blocks 20 are provided. As illustrated, a block, which embodies my invention, comprises a central vertical web 21 having a wide flange 22 extending along its upper and outer edges to support the fuel bed, and this flange is so constructed and arranged that adjacent blocks may contact with each other to form 85 a fairly close joint and prevent the escape of too much air therebetween, although it will be obvious that I may provide tuyère openings through this flange if desired.

In order to form one or more tuyère openings between adjacent blocks, I form a set of ribs on the web, and preferably on both sides thereof, and these ribs 23, 24 and 25 are so spaced and arranged that air may pass between them from the air chamber beneath the 90 blocks to the fuel bed. The ribs 23 form the bottom of the main portion of the block and are arranged to rest on the top corner portion 26 of the wall 10. The sides of the ribs 23 of adjacent blocks contact with each other and thus form a continuous surface touching the 100

retort top which prevents the leakage of air at this point and a consequent burning of the retort. The ribs 24 and 25 are arranged preferably parallel with the ribs 23, and they are all horizontally or otherwise disposed so that the fuel can not sift down through the openings between them.

As illustrated, the rib 23 is comparatively short, the rib 24 is slightly longer, and the 10 rib 25 very long, whereby a space 28 is formed which communicates with the outer ends of the passages between the ribs. The passages between these ribs are suitably proportioned and shaped as desired to furnish the required 15 amounts of air at the tuyère openings 30, 31 and 32 which communicate with the fuel bed. It will also be apparent that the sides of the ribs and flanges are formed in substantially the same plane, or otherwise arranged so that 20 adjacent blocks will fit against one another to form spaced tuyère openings and substantially continuous surfaces lying in contact with the fuel.

The top rib 25 is substantially coextensive 25 with the top flange 22 but is slightly shorter than the block, so as to leave a space between the outer end 33 of this rib and the vertical flanged portion 34 on the outside of the block. This space is substantially equal to the width 30 of the air channel between flange 22 and rib 25. It will therefore be seen that this arrangement is such that the top flange, the web portion and the ribs may all burn away to a position shown approximately by the line 35 $a-a$ without changing materially the size of the air openings to the fuel bed. Also, the top flange 22 may burn away until it reaches the outer end 33 of the rib 25 before fuel can escape downwardly through the tuyère openings. This construction is therefore one in 40 which the ribs 25 constitutes a secondary flange or supplementary fuel supporting structure for use as the upper flange burns away. The tuyère passages between the 45 other ribs are preferably provided with parallel walls so that the tuyère openings do not change in size.

The blocks may be suitably fastened in place, as by means of the depending portions 50 36 which are provided with apertures arranged to permit the passage of a rod 37 therethrough, this rod being adapted to be suitably fastened to the stoker parts to hold the tuyère blocks in position. The depending portion 55 36 of the tuyère block passes through an opening 38 suitably formed in the flat plate 16.

In view of the above disclosure, it will now 60 be seen that this invention is equally applicable to tuyère blocks used in other portions of the furnace, such as adjacent the side walls of the furnace, or between adjacent retorts, or wherever it is necessary to support the fuel and admit air thereto. This construction is such that one may secure satisfactory combustion within the stoker for a longer length

of time than heretofore obtainable with tuyère blocks of this type. During the effective life of the block, the tuyère openings remain substantially uniform in area, and fuel cannot sift through them into the air chamber 70 beneath the retort. This construction increases the efficiency of the stoker in that it prevents the formation of blow holes in the fire. Also, an additional cooling surface on the tuyère plates is provided by the use of 75 these long ribs of such extensive surface.

Having thus described my invention, what I claim as new and desire to secure by Letters Patent is:

1. A tuyère block comprising a thin web 80 adapted to be mounted vertically on a stoker, a laterally projecting, fuel supporting flange of substantially uniform width on the upper edge of the web and a set of spaced ribs projecting laterally from one side of the web to 85 form tuyère channels, the upper rib extending throughout the major portion of the length of the block and cooperating with the flange to form a long, narrow tuyère channel and a secondary fuel support. 90

2. A tuyère block comprising a thin web adapted to be mounted vertically on a stoker, a fuel supporting flange extending along the top edge of the web, a top rib on the side of the web substantially coextensive and parallel 95 with the flange which serves as a secondary fuel support and cooperates with the flange to form a long tuyère channel of substantially uniform air conductive capacity throughout its length and a long rib beneath and cooperating with the top rib to form a further secondary fuel support and a long tuyère channel. 100

3. A tuyère block comprising a thin web adapted to be mounted vertically on a stoker, 105 a flange on the top edge of the web, a set of spaced ribs on one side of the web which form tuyère channels leading to tuyères on one end of the block and a flange on the opposite end of the block from the tuyères, the top rib extending from the tuyère end nearly to the end flange and cooperating with both flanges to form a long, narrow channel having an inlet near the end flange which controls the flow of air through the channel. 110

4. A tuyère block comprising a thin web adapted to be mounted vertically on a stoker, a fuel supporting flange of uniform width on the top of the web and projecting laterally from both sides thereof and a set of spaced 120 ribs on each side of the web which cooperate to form tuyère channels, the top ribs being substantially horizontal and extending throughout the major portion of the length of the block to form a secondary fuel support. 125

5. A tuyère block comprising a web adapted to be mounted vertically on a stoker, a laterally extending, fuel supporting flange on the top edge of the web, a top rib on the web which is spaced from the flange and extends 130

throughout the major portion of the length of the block to form a secondary fuel support and a long tuyère channel, and long spaced ribs beneath the top rib which form further 5 secondary fuel supports and long tuyère channels.

6. A tuyère block comprising a thin web arranged to be mounted in a stoker vertically above an air passage, a flange on the upper 10 edge of the web having a top arranged to support the fuel and ribs on the side of the web extending inwardly from the tuyère edge of the block for progressively increasing distances from the lowermost to the top rib, said 15 flange and ribs cooperating to form tuyère channels, the inlet ends of which are substantially horizontally spaced and directly receive the air ascending thereto from said passage, and the top rib extending through-

out the major portion of the length of the 20 block.

7. A tuyère block comprising a thin web adapted to be mounted vertically on a retort wall, a flange along the top, a substantially vertical flange on one end of the web, a series 25 of long spaced ribs substantially parallel with the top flange which extend from the end of the web opposite the vertical flange but are progressively shorter in length from the top to the bottom of the block, the upper rib 30 extending nearly to the vertical flange and being so arranged relative to the top flange as to form a narrow tuyère channel and to serve as a secondary fuel support.

Signed at Worcester, Massachusetts, this 35
15th day of June, 1925.

OSCAR A. JOHNSON.
